UNITED STATES PATENT OFFICE.

VINTON E. SISSON, OF CHICAGO, ILLINOIS, ASSIGNEE TO WALTER P. MURPHY, OF CHICAGO, ILLINOIS.

SHEET-METAL CAR END.

1,254,860.

Specification of Letters Patent. Patented Jan. 29, 1918.

Application filed October 18, 1913. Serial No. 794,951.

To all whom it may concern:

Be it known that I, VINTON E. SISSON, a citizen of the United States, residing at Chicago, in the county of Cook and State of Illinois, have invented certain new and useful Improvements in Sheet-Metal Car Ends of which the following is a specification.

My invention relates to the construction of railway cars, particularly box cars, and has for its principal object to provide a sheet metal end structure for railway cars which will be so constructed and its parts so connected together and reinforced as to give said end structure great strength and capacity for resisting deflection as against the stresses and pressures that are exerted against the end of railway cars while in service due particularly to the shifting of the cargoes.

20 A further object is to provide a sheet metal car end composed of a plurality of sheets or panels which are of such character that they may be conveniently and inexpensively manufactured and readily assembled and attached to the framing of the car.

The invention consists in the constructions, arrangements and devices for carrying out these objects hereinafter described and claimed in the appended claims.

30 The invention is illustrated, in certain preferred embodiments, in the accompanying drawings, wherein—

Figure 1 is an end elevation of a railway box car of ordinary construction fitted with a sheet metal end structure constructed in accordance with the principles of the invention.

Fig. 2 is a sectional view on line 2—2 of Fig. 1;

40 Fig. 2^a, a fragmentary sectional view, similar to Fig. 2, showing a modification;

Fig. 3, a detailed sectional plan on line 3—3 of Fig. 1;

Fig. 4, an end elevation illustrating a 45 modification;

Fig. 5, a section on line 5—5 of Fig. 4;

Fig. 6, a fragmentary end elevation of another modified construction;

Fig. 7, a vertical sectional view of this 50 construction, and

Fig. 8, a sectional plan on line 8—8 of Fig. 7.

Like characters of reference designate like parts in the several figures of the drawings.

Referring to the drawings which show the end structure of my invention applied to a box car of familiar construction, though obviously the invention is not limited thereto, 10 designates the end sill at one end of the car, 11 the end plate, 12 the corner posts, 13 the side girths, 14 the side plates, and 15 the side sills.

The end structure comprises a corrugated panel made up of a plurality of sections or sheets. In the construction shown in Figs. 1 to 3 inclusive, there are three of these sections, an upper section 16, a lower section 17 which are duplicates and may be pressed from the same set of dies, and an intermediate section 18 which is preferably narrower than the upper and lower sections. The intermediate section is preferably formed with a pressed out rib or corrugation 19 which preferably extends across the intermediate member to points close to the opposite ends thereof. Preferably the intermediate member is formed with angular flanges 20 which overlap the corner posts 12 and are secured thereto by any suitable means; for example, 25 bolts 21. The upper and lower sections are formed with stiffening ribs preferably extending horizontally across the sheets from side to side, as indicated at 22. The corrugations are preferably spaced apart distances substantially equal to their width so that the corrugated portions of the sheet, in each case, consist, in effect, of a plurality of contiguous ribs projecting alternately in opposite directions from each other which 30 function as beams, of substantially equal strength, to carry the stresses to the side frame members of the car. The lower edge of the upper section and the upper edge of the lower section are secured to the margins 35 of the intermediate member above and below its strengthening rib 19, preferably overlapping said margins, the edges of the upper and lower sheet being preferably cut out, as indicated at 23, to fit closely around the 40 corrugation 19. This arrangement, besides giving strength and stiffness to the structure, resisting deflection and the breaking out of the end by shifts of the cargo, provides a waterproof connection between the 45 sections which is a matter of very considerable importance. The upper and lower sections are preferably provided with angular flanges 24 secured to the corner posts 12 by the bolts 21 above mentioned, and by a 50

55

- suitable number of other bolts designated 25. The upper end of the upper section is secured to the end plate by bolts 26. The lower edge of the lower section may over-
 5 lap the end sill 10 and be secured thereto by bolts 27 (as shown in Figs. 1 and 2) or it may be bent and turned in and secured to the upper face of the end sill by bolts 28 as shown in Fig. 2^a. Preferably a fascia 10 29 is used for covering the upper edge of the upper section so as to weatherproof the end at this place. In order to more firmly anchor the end sheets to the framing of the car I preferably provide angular gussets 30
 15 near the upper corners of the upper sections and the lower corners of the lower sections, which are secured to the corner posts and to the side plates 14 and side sills 15, respectively.
 20 The construction shown in Figs. 4 and 5 is the same as that shown in Figs. 1 and 2, except that the upper and lower edges of the upper and lower sections, here designated 16^a, 17^a, respectively, are straight instead of 25 being cut to fit the corrugation 19 of the intermediate section and except that the upper edge of the lower section underlaps instead of overlaps the adjacent edge of the intermediate section with the advantage 30 that the structure is more surely waterproof along the line of junction of these sections.
 In the construction shown in Figs. 6 to 8 inclusive, there are two duplicate sections 16^b, 17^b, the lower edge of the upper section and the upper edge of the lower section being formed with flanges 31, 31 which extend into the pressed out rib 19^b of the intermediate section 18^b and are secured thereto by rivets 32; the ends of the intermediate 40 section being preferably widened as shown at 33. Otherwise the construction may be the same as shown in the preceding figures.
 While I have described my invention as embodied in certain preferred constructions, 45 it will be obvious that modifications might be made without departure from the principle of the invention. Therefore I do not wish to be understood as limiting the invention to the precise constructions, arrangements, devices and proportions shown, except so far as such limitations are specifically made in the claims.

I claim:

1. A car end comprising an upper section and a lower section each provided with stiffening ribs and an intermediate section provided with a horizontal stiffening rib, the edges of the upper and lower sections connected to said intermediate section being 55 similarly cut away so as to fit the corrugation of the intermediate section.
2. In a railway car, the combination with the longitudinal frame members of the car, of a sheet metal end panel formed with a plurality of horizontal corrugations and

means for securing the vertical edges of said panel, at the corners of the panel, to the respectively adjacent longitudinal frame members of the car.

3. In a railway car, the combination with the longitudinal frame members of the car, of a sheet metal end panel formed with a plurality of horizontal corrugations, and means for securing the vertical edges of said panel, at the corners of the panel and at 75 points intermediate said corners, to the respectively adjacent longitudinal frame members of the car.

4. In a railway car, the combination with the longitudinal frame members of the car, of a sheet metal end panel formed with a plurality of horizontal corrugations and means for securing the vertical edges of said panel, at the corners of the panel, to the respectively adjacent longitudinal frame members of the car, said panel being provided at its vertical edges with angularly disposed flanges which rigidify said edges and serve in part as the means for making said attachments to the longitudinal frame members. 85

5. In a railway box car, the combination with the side sills and side plates of the car, of a sheet metal end panel formed with a plurality of horizontal corrugations extending 95 across the car end from side to side, and attaching members for securing the upper and lower corners of the panel to the side plates and side sills, respectively.

6. In a railway box car, the combination with the side sills, side plates and side girders of the car, of a sheet metal end panel formed with a plurality of horizontal corrugations extending across the car end from side to side, attaching members for securing the upper and lower corners of the panel to said side plates and side sills, respectively, and attaching members for securing the panel at points intermediate its corners to the side girders of the car. 100

7. In a railway box car, the combination with the wooden side sills, side plates and corner posts of the car, of a sheet metal end panel formed with a plurality of horizontal corrugations extending across the car end from side to side, and attaching members for securing the upper and lower corners of the panel to said side plates and side sills, respectively; said panel being provided at its vertical edges with angularly disposed 115 flanges which overlap and are secured to said corner posts.

8. In a railway box car, the combination with the wooden side sills, side plates and corner posts of the car, of a sheet metal end panel formed with a plurality of horizontal corrugations extending across the car end from side to side, and attaching members for securing the upper and lower corners of the panel to said side plates and side sills, 125 130

- respectively; said panel being provided at its vertical edges with angularly disposed flanges which overlap and are secured to said corner posts, said flanges forming in part the means for attaching the panel to said side plates and sills.
9. In a railway box car, the combination with the wooden side sills, side plates, side girds and corner posts of the car, of a sheet metal end panel formed with a plurality of horizontal corrugations extending across the car end from side to side, and provided with angularly disposed flanges along its vertical edges which overlap and are secured to said corner posts, and attaching means for securing said flanges to the side plates, said girds and said sills of the car.
10. In a railway car, the combination with the longitudinal frame members of the car, of a sheet metal end panel formed with a plurality of horizontal corrugations and means for securing the vertical edges of said panel, at the corners of the panel, to the respectively adjacent longitudinal frame members of the car; said corrugations being spaced apart distances substantially equal to their width, whereby the corrugated portion of the panel forms in effect a series of ribs, functioning as beams, which project alternately in opposite directions one from the other.
11. In a railway box car, the combination with the wooden side plates, side sill, side girds and corner posts of the car, of a sheet metal end panel provided with angular flanges overlapping and secured to the side and front faces of the corner posts and formed with horizontal corrugations extending across the panel so as to transmit stresses to the corner posts, and attaching members at the upper and lower corners of the panel and at points intermediate thereof for securing said panel to the side plates, side sills, and side girds, respectively.
- 45 12. In a railway box car, the combination with the wooden side plates, side sills, side girds and corner posts of the car, of a sheet metal end panel provided with angular flanges overlapping and secured to the side and front faces of the corner posts and formed with horizontal corrugations extending across the panel so as to transmit stresses to the corner posts, and attaching members at the upper and lower corners of the panel and at points intermediate thereof for securing said panel to the side plates, side sills, and side girds, respectively, said corrugations being spaced apart distances substan-
- tially equal to their width whereby the corrugated portion of the panel forms in effect a series of ribs which project alternately in opposite directions one from the other.
13. In a railway car, the combination with the framing of the car, of a sheet metal end panel comprising metallic end sheets formed with parallel corrugations and means for securing said sheets together, which forms a rigidifying element extending across the panel parallel to said corrugations; said corrugations being spaced apart distances substantially equal to their widths so as to provide a series of ribs, functioning as beams of substantially equal strength, which project alternately in opposite directions one from the other.
14. In a railway car, the combination with the framing of the car, of a sheet metal end panel comprising metallic end sheets formed with parallel corrugations and means for securing said sheets together, which forms a rigidifying element extending across the panel parallel to said corrugations; said corrugations being spaced apart distances substantially equal to their widths so as to provide a series of ribs, functioning as beams of substantially equal strength, which project alternately in opposite directions one from the other; said car being provided with frame members to which the edges of the panel at the ends of the corrugations are attached, respectively, and the panel with angularly disposed flanges which overlap and rigidify said frame members.
15. A sheet metal end structure for a railway car comprising an end sheet formed with a plurality of horizontal corrugations which terminate within the edges of the sheet so as to leave flat stiffening margins at the sides of said sheet, said corrugations being spaced apart distances substantially equal to their widths whereby the entire corrugated portion of the sheet, between the flat margins, forms a plurality of ribs of substantially equal strength projecting alternately in opposite directions one from the other; said flat margins being provided with stiffening members which extend at right angles to the plane of the sheet and are in rigid relation to the frame of the car so as to constitute upright beams to take the stresses on said horizontal corrugations.
